NON-DETACHABLE EASY-OPEN END CLOSURE

Daniel F. Cudzik, Richmond, Va., assignor to Reynolds
Metals Company, Richmond, Va.

Filed May 17, 1973, Ser. No. 361,168

Term of patent 14 years

Int. Cl. D9—07

U.S. Cl. D9—255

FIG 1.

FIG 2.

FIG 3.

FIG 4.

FIG. 1 is a perspective view of a non-detachable easy-end closure showing my new design;

FIG. 2 is a top plan view;

FIG. 3 is a cross-sectional view taken along line 3—3 of FIG. 2;

FIG. 4 is a perspective view showing the tear strip and tab in an opened position;

FIG. 5 is a top plan view of the FIG. 4 representation;

FIG. 6 is a cross-sectional view taken along line 6—6 of FIG. 5;

FIG. 7 is a perspective view showing the tear strip opened and the tab returned to a horizontal position.

I claim:

The ornamental design of a non-detachable easy-open end closure, substantially as shown and described.
